MACHINE FOR INSERTING COLLARS IN
METAL CANS

Alfred L. Kronquest, Syracuse, N. Y., assignor to
Continental Can Company, Inc., New York,
N. Y., a corporation of New York

Application June 30, 1933, Serial No. 678,500

10 Claims. (Cl. 113—1)

The invention relates to new and useful improvements in a machine for inserting a collar in a metal can.

An object of the invention is to provide a machine wherein a centering ring may be utilized for rounding up a can body and for rounding up a collar and directing said collar into said can body.

A further object of the invention is to provide 10 a machine of the above type with means operating to first force the can body into the centering ring for rounding up the same and then forcing the collar into and through the centering ring into the can body.

15 A still further object of the invention is to provide a machine of the above type having a plurality of collar inserting units which are automatically supplied with can bodies and collars to be inserted in said can bodies and wherein 20 said machine is provided with means for stopping the moving parts in case of a jam.

These and other objects will in part be obvious and will in part be hereinafter described.

In the drawings:

25 Fig. 1 is a vertical sectional view through a machine embodying the improvements.

Fig. 1a is an enlarged detail showing a portion of a clutch mechanism which is automatically released in case of a jam.

30 Fig. 2 is a sectional view on the line 2—2 of Fig. 1.

Fig. 3 is a sectional view on the line 3—3 of Fig. 1.

Fig. 4 is a sectional view on the line 4—4 of Fig. 1.

Fig. 5 shows a can body with a collar inserted therein by the improved collar inserting machine.

Fig. 6 shows a finished can body with the collar fully seated and with an end double seamed thereto.

Fig. 7 is a view showing more or less diagrammatically the position of the parts when the can body and the collar first pass into the collar inserting unit.

Fig. 8 is a view showing the can body rounded up by the centering device preparatory to receiving the collar.

Fig. 9 is a view showing the collar placed in the can body to the full extent to which it is forced into the can body by the machine.

Fig. 10 shows a can body and inserted collar stripped from the centering ring and ready for discharge from the machine.

It is a common expedient to provide a can body having scoring lines setting off the tearing strip

with an inserted collar which frictionally engages the inner wall of the can body and overlies the tearing strip so that when said tearing strip is removed the collar will provide a smooth upper edge on the can body and give to the can body its maximum capacity when opened.

It has been a common practice to flange a can body and then force a collar into said flanged can body. There are advantages in forcing the collar into the can body before it is flanged and in the flanging of the can body simultaneously with the seating of the collar therein. Such a method of seating a collar in a can body is shown described and claimed in my prior application Serial No. 593,916, filed February 18, 1932.

The present invention has particularly to do with a machine for the preliminary insertion of the collar in the can body preparatory to submitting of the same to a machine for the final seating of the collar and the flanging of the can body. The machine is provided with a rotating turret carrying a plurality of collar inserting units. Means is also provided for automatically feeding a can body and a collar which is to be inserted therein to each unit as it passes a loading station. Each collar inserting unit includes a centering ring which performs the double function of centering and rounding up the can body and also for centering and rounding up the collar for insertion therein. The can body is first caused to contact with the centering ring for rounding up and positioning the same for insertion of the collar, after which the collar is forced through the centering ring and is thus rounded up and centered and caused to enter the can body. After the collar has been properly seated in the can body, then the plunger which seats the collar operates to strip the collar and can body from the centering ring for discharge from the machine.

Referring more in detail to the drawings, the improved machine consists of a supporting base 1, on which is mounted an intermediate frame section 2, which in turn carries an upper frame structure 3. Mounted for rotation in this upper frame structure 3 is a shaft 4. Said shaft 4 is provided with a gear wheel 5 which meshes with a pinion 6 on a main actuating shaft 7. Said shaft 7 is driven in any suitable way from a driving wheel 8 and is connected thereto manually through a clutch means 9.

The shaft 4 is mounted for rotation in a supporting bearing 10 at one end of the upper frame and a supporting bearing 11 at the other end of said frame. Keyed to the shaft 4 and rotating

therewith is a skeleton supporting turret 12 which, as shown in Fig. 3 of the drawings, is provided with three semi-cylindrical supporting pockets 13, 14 and 15. Mounted in each pocket is a can body supporting plate 16. Also mounted in each pocket is a collar receiving plate 17 which carries a centering ring 18, preferably formed integral therewith.

The can body in which the collar is to be inserted is indicated more or less diagrammatically at 19 in Fig. 5 of the drawings. Said body is provided with a bead 20 a short distance back from the open end thereof and the open end which is to receive the collar, is unflanged. That is, it is of uniform inner diameter. The collar is indicated at 21. Said collar is preferably provided with a curled outer edge 22 which makes a smooth edge for the hand to contact with and which strengthens the collar and aids in maintaining its cylindrical shape. The wall of the collar is provided with an outwardly projecting bead 23, which is so dimensioned as to make a very tight frictional contact with the inner wall of the can body.

The purpose of the present machine is to insert the collar in the can body before the body wall is flanged and preferably only to seat the collar partially in the can body, as indicated in Fig. 5. In the completion of the can body the collar is forced down onto the bead 20; the body wall is flanged and then a closing end 24 is placed on the can body and secured thereto by a double seam 25. This type of can is shown, described and claimed in my co-pending application Serial No. 593,915, filed February 18, 1932.

The can bodies are conveyed to the machine by a suitable conveying chute including guide rails 26 and 27, see Fig. 3. This same chute for guiding the bodies, is also used for guiding the collars 21 and a guiding partition 28 serves to keep the can body and collar separated, see Fig. 1. As the shaft 4 rotates, the pockets are moved one at a time beneath the discharge end of the chute for the can bodies and the collars and said collars and can bodies are fed by gravity into the pockets therefor in the rotating turret. The turret rotates continuously and when there is a can body or collar in place, it will operate to hold the next succeeding collar or can body from entering the pocket. The turret between the pockets is provided with a cylindrical face 29 on which the can bodies and collars in the chute rest between the passing of the pockets. There is a stationary curved guide rail 30 associated with the turret 55 which contacts with the outer face of the can body and also the collar and retains the same in the pockets in the turrets until the collar has been inserted in the can body. The portion of the guide rail from the point 31 to the point 32 is concentric with the center of rotation of the turret and from the point 32 to the point 33 said rail curves away from the center of rotation of the turret so as to permit the can bodies with the collars attached to drop by gravity from the pockets.

The centering ring, as shown more clearly in Figs. 7 to 10, is provided with a central cylindrical portion 34, which is of substantially the same diameter as the inner diameter of the can body. At one side of this central portion there is a tapering portion 35, which is adapted to receive the can body for rounding up and centering the same in alignment with the cylindrical wall 34. The can body is dropped into the pocket along-

side of the centering ring and is subsequently moved endwise into contact with this tapering portion for rounding up the can body if it is out of round and for centering the same in the manner stated above. At the other side of the centering ring there is a tapered surface 36 which is adapted to center and round up the collar so that it will pass through the centering ring.

The can body is forced into contact with the centering ring by a reciprocating head 37 which is mounted on a rod 38 carried by a support 39, which is fixed to the shaft 4 and rotates therewith. This support 39 is provided with a flat face 40 for each collar inserting unit. Said supporting member 39 has upstanding ledges 41 and 42 between which are placed guide rails 43 and 44. The rod 38 slides between these guide rails. Said rod is beveled so as to underlie the beveled faces on the guide rails. The guide rail 44 may be positioned by means of adjusting screws 45. This rod 38 carries a roller 46 which runs in a cam race 47 in a stationary cam 48. The stationary cam 48 is fixed to a threaded sleeve 49. This sleeve 49 serves as a supporting bearing for the shaft 4, and is mounted on a bearing bracket 50 carried by the upper frame. The sleeve is keyed to the bracket and while it can move endwise, it does not rotate in the bracket. Collars 51 and 52 have a threaded engagement with the sleeve and bear against the end faces of the bracket. This provides a means whereby the sleeve 49, together with the stationary cam and the rod 38 and the head 37 operated thereby, can be shifted to different set positions for can bodies of different lengths.

The collar 21 is moved into the centering ring and through the same by a head 53. There is a head associated with each collar inserting unit. This head is carried by a plunger 54 which is mounted for reciprocation in a supporting member 55, which is fixed to the shaft 4 and rotates therewith; said support 55 is provided with sleeves 56, 57 in which said plunger reciprocates. A link 57 is attached to the plunger and to a crank 58 carried by a shaft 59 located radially of the shaft 4 and mounted in bearings in the support 55, said shaft 59 is provided with a beveled gear 60 which meshes with a stationary beveled gear 61, fixedly mounted in the bracket 62. The sleeve carrying the beveled gear 61 is attached to the bracket and serves as a bearing sleeve for the shaft 4. The supporting member 55 turns with the shaft 4 and this causes the beveled gears 59 to rotate, which in turn rotate the crank 58 and this through the links 51 reciprocates the plungers 54. The crank is so timed that the head 53 does not contact with the collar for moving the same through the centering ring until after the head 37 operated by the stationary cam 46 has contacted with the can body and moved the same to the position shown in Fig. 8. This insures that the can body if out of round will be brought back into cylindrical form through the action of the tapered surface 35 contacting with the end of the can body and said can body will be positioned in the centering ring so that the inner surface of the can body is substantially in line with the cylindrical surface 34 of the centering ring. After the can has brought the can body thus into contact with the centering ring, it remains inactive and holds the can body in this position, serving as an abutment for the can body. The crank now becomes effective to move the head 53 into contact with the collar 21 and forces said collar through the centering 75

ring, rounding it up as it contacts with the tapered face 36. The collar is forced into the can body to the position shown in Fig. 9, after which the head 37 is moved away from the can body and at a slightly greater speed than the movement of the head 53 bearing on the collar. Thus it is that the head 53 will move the can body and the inserted collar so as to strip the same from the centering ring and the can body will move along the guide rails 30 and be discharged from the machine. The can body is stripped from the ring when the turret has turned through an arc of approximately 180° and therefore said can body is released from the turret when at the lower side of the turret and can by gravity be discharged from the pocket. It is understood that the collar is so dimensioned that it has a very tight frictional engagement with the can body and it is positively forced into the can body to the desired extent, after which the can body is released so as to bring about the stripping action just referred to.

The gear 5 is freely mounted on the shaft 4 and there is a clutch for connecting this gear to the shaft. Attached to the gear 5 is a hardened metal disk 63. Attached to the shaft for rotation therewith is a clutch member 64 carrying a hardened metal disk 65. The two disks are provided with recesses which face each other and which are the same distance from the center of the shaft. Balls 66 are placed in these recesses when they are in alignment and a spring 67 bearing against the clutch member 64 forces the metal disk carried thereby yieldingly against the balls and the balls against the metal disk 63. The clutch member 64 is free to move endwise on the shaft but, as noted, it rotates with the shaft and therefore when the balls are in the recesses, the clutch member is connected to the gear 5 so that the rotating of the gear 5 will cause the shaft 4 to be rotated. If for any reason there is a jam in the machine which stops the rotation of the turret or the reciprocation of the heads seating the collar in the can body, then the spring 67 will yield to allow the shaft 4 to continue to rotate without the breaking of parts. When the clutch member 64 is forced to a position so that the balls are unseated, there is a locking finger 68 which moves down into the path of the yoke 69 and holds the clutch member separated. This yoke 69 is pivoted at 70 and carries a hardened plate 71. The finger 68 is pivoted at 72 to a hand lever 73 and a spring 74 serves to turn the hand lever 73 in a clockwise direction and force the finger downwardly. Normally the finger rests on the yoke until the clutch member is forced to the left as viewed in Fig. 1a and then the spring 74 will force the finger into the path of movement of the yoke and thus positively hold the clutch member 64 in a position so that the main shaft 4 can turn without turning the shaft 7. After the jam has been released the operator can move the hand lever 73 so as to release the yoke and the balls will at once become seated in a recess and take up the drive of the turret carrying the collar seating units.

While there has been shown and described in detail a particular type of collar which is inserted in a can body that has not been flanged, it will be understood from certain aspects of the invention that the machine may be used for inserting collars of other forms in can bodies which have or have not been flanged.

It is obvious also that minor changes in the details of construction and the arrangement of the parts may be made without departing from the spirit of the invention as set forth in the appended claims.

Having thus described the invention, what I claim as new and desire to secure by Letters Patent is:

1. A machine for inserting a collar in a metal can body comprising a support for the can body, a support for the collar, a centering ring, said ring having means for rounding up and positioning the can body to receive the collar, means for rounding up the collar, and means disposed between the rounding up means for the body and the collar for directing the collar into said can body, means for engaging said can body for forcing the same into the centering ring and means engaging said collar for forcing the same through the ring and into the can body.

2. A machine for inserting a collar in a metal can body comprising a support for the can body, a support for the collar, a centering ring, said ring having means for rounding up and positioning the can body to receive the collar means for rounding up the collar, and means disposed between the rounding up means for the body and the collar for directing the collar into said can body, means for engaging said can body for forcing the same into the centering ring and means engaging said collar for forcing the same through the ring and into the can body, said means operating to move the can body being timed relative to the collar moving means so that said collar and can body after they are assembled are stripped from the centering ring and released from the machine.

3. A machine for inserting a collar into a metal can body comprising a support for the can body, a support for the collar, a centering ring having a tapered face adapted to receive and round up the end of the can body and a tapered face at the other side thereof adapted to receive and round up the collar, and a substantially horizontal face between said tapered faces of substantially the same diameter as the inner diameter of the can body for directing said collar into said can body.

4. A machine for inserting a collar in a metal can body comprising a rotating turret, a can body supporting plate carried thereby, a collar support carried by said turret, a centering ring carried by the turret and located between the can body support and the collar support, means for placing can bodies and collars on the supports therefor while the turret is moving, said centering ring having means for rounding up and positioning said can body to receive the collar and having means for directing the collar through the centering ring into the can body, means traveling with the turret for engaging said can body for forcing the same into the centering ring and means traveling with the turret for engaging said collar for forcing the same through the ring and into the can body.

5. A machine for inserting a collar in a metal can body comprising a rotating turret, a can body supporting plate carried thereby, a collar support carried by said turret, a centering ring carried by the turret and located between the can body support and the collar support, means for placing can bodies and collars on the supports therefor while the turret is moving, said centering ring having means for rounding up and positioning said can body to receive the

- collar and having means for directing the collar through the centering ring into the can body, means traveling with the turret for engaging said can body for forcing the same into the centering ring and means traveling with the turret for engaging said collar for forcing the same through the ring and into the can body, said means operating to move the can body being timed relative to the collar moving means so that said collar and can body after they are assembled are stripped from the centering ring and released from the machine.
6. A machine for inserting a collar in a metal can body comprising a rotating turret having a plurality of collar inserting units, each of which includes a can body supporting means, a collar supporting means, a centering ring located between the can body supporting means and the collar supporting means, said centering ring having means for rounding up and positioning the can body to receive the collar and having means for directing the collar through the centering ring into the can body, means carried by said turret and associated with each centering ring for forcing said can body into the centering ring and means traveling with said turret and associated with said centering ring for forcing the collar through the ring and into the can body.
7. A machine for inserting a collar in a metal can body comprising a rotating turret having a plurality of collar inserting units, each of which includes a can body supporting means, a collar supporting means, a centering ring located between the can body supporting means and the collar supporting means, said centering ring having means for rounding up and positioning the can body to receive the collar and having means for directing the collar through the centering ring into the can body, means carried by said turret and associated with each centering ring for forcing said can body into the centering ring and means traveling with said turret and associated with said centering ring for forcing the collar through the ring and into the can body.
8. A machine for inserting a collar in a metal can body comprising a rotating turret having a plurality of collar inserting units, each of which includes a can body supporting means, a collar supporting means, a centering ring located between the can body supporting means and the collar supporting means, said centering ring having means for rounding up and positioning the can body to receive the collar and having means for directing the collar through the centering ring into the can body, means carried by said turret and associated with each centering ring for forcing said can body into the centering ring and means traveling with said turret and associated with said centering ring for forcing the collar through the ring and into the can body, means for forcing said can body into the centering ring, means traveling with said turret and associated with said centering ring for forcing the collar through the ring and into the can body, means for rotating said turret, means for feeding can bodies and collars in succession to the inserting units while said turret is rotated.
9. A machine for inserting a collar in a metal can body comprising a rotating turret having a plurality of collar inserting units, each of which includes a can body supporting means, a collar supporting means, a centering ring located between the can body supporting means and the collar supporting means, said centering ring having means for rounding up and positioning the can body to receive the collar and having means for directing the collar through the centering ring into the can body, means carried by said turret and associated with each centering ring for forcing said can body into the centering ring, means traveling with said turret and associated with said centering ring for forcing the collar through the ring and into the can body, means for rotating said turret, means for feeding can bodies and collars in succession to the inserting units while said turret is rotated, said means for rotating the turret including clutch members yieldingly pressed into engagement and constructed so that in case of a jam said clutch members will separate and stop the rotation of the turret and release the turret from the rotating means therefor.
10. A machine for inserting a collar in a metal can body comprising a rotating turret having a plurality of collar inserting units, each of which includes a can body supporting means, a collar supporting means, a centering ring located between the can body supporting means and the collar supporting means, said centering ring having means for rounding up and positioning the can body to receive the collar and having means for directing the collar through the centering ring into the can body, means carried by said turret and associated with each centering ring for forcing said can body into the centering ring, means traveling with said turret and associated with said centering ring for forcing the collar through the ring and into the can body, means for rotating said turret, means for feeding can bodies and collars in succession to the inserting units while said turret is rotated, said means for rotating the turret including clutch members yieldingly pressed into engagement and constructed so that in case of a jam said clutch members will separate and stop the rotation of the turret and release the turret from the rotating means therefor.
11. A machine for inserting a collar in a metal can body comprising a rotating turret having a plurality of collar inserting units, each of which includes a can body supporting means, a collar supporting means, a centering ring located between the can body supporting means and the collar supporting means, said centering ring having means for rounding up and positioning the can body to receive the collar and having means for directing the collar through the centering ring into the can body, means carried by said turret and associated with each centering ring for forcing said can body into the centering ring, means traveling with said turret and associated with said centering ring for forcing the collar through the ring and into the can body, means for rotating said turret, means for feeding can bodies and collars in succession to the inserting units while said turret is rotated, said means for rotating the turret including clutch members yieldingly pressed into engagement and constructed so that in case of a jam said clutch members will separate and stop the rotation of the turret and release the turret from the rotating means therefor, and an automatic means for holding said clutch members separated until said automatic means is manually released.

ALFRED L. KRONQUEST.
